PHONOGRAPH RECORD SHAVING MACHINE

Richard M. Somers, West Orange, N. J., assignor
to Thomas A. Edison, Incorporated, West
Orange, N. J., a corporation of New Jersey

Application June 25, 1938, Serial No. 215,948

29 Claims. (Cl. 82—1.1)

This invention relates to machines for shaving or resurfacing phonograph records principally of the type intended for use with dictating machines. This invention is particularly concerned with improvements in such machines which are adapted to improve the operation of the machine and to prevent the operator from inadvertently performing operations in the use of the machine which may result in damage to the machine or to the records to be resurfaced.

The operation of shaving a record involves the mounting of a record on the machine, the conditioning and operating of the machine so as to effect the resurfacing of the record, and the removal of the record from the machine. In order to effect such a shaving operation, a series or cycle of manipulations must be performed on the machine. These recurring manipulations, as in the performance of successive shaving operations, are desirably performed in a suitable selected sequence in order to insure the safe and proper operation of the machine. Moreover, in order to render the machine more conveniently operable, some manipulations may be automatically performed incidental to the performance of others. In this connection the machine may be also arranged so that the performance of the terminal manipulations of one cycle may automatically effect the operations normally performed by the initial manipulations of a subsequent cycle; as the operator completes the resurfacing of a record and removes the record from the machine, the machine will then be already partially conditioned for a resurfacing operation on a subsequent record.

It is an object of my invention to provide, in phonograph record shaving machines, improvements adapted to facilitate the operation of the machine and to safeguard the machine against improper usage.

It is another object of my invention to provide means in record shaving machines for partially conditioning the machine for another resurfacing operation as an incident of completing a previous resurfacing operation.

It is another object of my invention to provide, in phonograph record shaving machines, means for preventing the removal of a record from the machine while the resurfacing tool is in set or operative position.

It is a further object of my invention to provide means for rendering the record ejecting means inoperative while the resurfacing tool is in operative position.

It is another object of my invention to provide,

in record shaving machines, means for partially returning the carriage to its initial position as an incident of removing a record from the machine.

It is a further object to provide means for imparting return movement to the carriage as an incident of operating the record ejecting means.

It is another object of my invention to provide means, in record shaving machines, for preventing damage to the carriage feeding means while the carriage is returned to initial position.

It is a further object of my invention to provide auxiliary means, in record shaving machines, for preventing movement of the carriage towards its initial position except when the feed- 15 nut is wholly disengaged from the feed screw.

It is another object of my invention to provide, in record shaving machines, an improved form of resurfacing tool setting mechanism which is adapted to enable the resurfacing tool to be 20 repeatedly set at substantially even depths of cut.

Other objects and features of my invention will more fully appear from the following description and the appended claims.

In the description of my invention reference is 25 had to the accompanying drawings, of which:

Figure 1 is a top plan view of a phonograph record shaving machine showing my invention applied thereto;

Fig. 2 is a vertical cross sectional view taken 30 along the line 2—2 of Fig. 1;

Fig. 3 is a vertical cross sectional view, taken along the line 3—3 of Fig. 1, showing the means controlled by the resurfacing tool for locking the record ejecting means;

Fig. 4 is a side elevational view of auxiliary means for manually releasing the resurfacing tool from operative position, the frame of the machine being shown in cross section;

Fig. 5 is a front vertical cross sectional view of 40 a portion of the machine taken along the line 5—5 of Fig. 1;

Fig. 6 is a fragmentary front elevational view of the record ejecting means and mandrel brake, the frame of the machine being shown in cross 45 section;

Fig. 7 is a side elevational view of a portion of the machine, partly in cross section, showing, in particular, details of the setting mechanism for the resurfacing tool, and means controlled in 50 accordance with the setting of the resurfacing tool for locking the end gate in its supporting position;

Fig. 8 is a fragmentary front elevational view of the record ejecting means and a front eleva- 55

tional view of the means connected with the record ejecting means for partially returning the carriage, and showing the means for restricting the further return movement of the carriage;

5 Fig. 9 is an enlarged cross sectional view taken along the line 9—9 of Fig. 7; and

Fig. 10 is an enlarged fragmentary view, partly in elevation and partly in cross section, showing details of the means for supporting and clamp-
10 ing the knife bar of the resurfacing tool.

Reference being had to Fig. 1 there will be seen a form of phonograph record shaving machine in which my invention is preferably employed. This machine comprises a base plate 1 having a left-hand standard 2, right-hand standards 3 and 4 and an intermediate standard 5. The standard 2 supports a conically pointed stud 6 which engages a recess in the left end of a shaft 7 to provide a thrust bearing for the shaft. The shaft 7 passes through an oversized hole 8 in the standard 5 and carries a mandrel 9 for holding a cylindrical record 10 to be resurfaced. The right end of the shaft 7 is supported by another thrust bearing comprising a conically pointed stud 11 which engages a recess in the right end of the shaft. The stud 11 is carried by an end gate 12, and is adjustable relative thereto by an adjusting screw 13 well known in the art.

30 The end gate 12 is pivoted to a boss 14 (see Fig. 7) so that it may be opened or swung outwardly from its supporting position, shown in Fig. 1, to a non-supporting position wherein it is free of the right end of the mandrel 9, thereby permitting a record to be mounted on or to be removed from the mandrel. The end gate 12 may be closed or moved into its supporting position by imparting a clockwise movement thereto until its forward extremity impinges against the right end of a guide rail 15 which extends laterally along the forward part of the machine, the end gate being releasably held in its supporting position by a latch 16. When the end gate 12 is open the shaft 7 is intermediately supported by the intermediate standard 5; in this case the shaft will tend to move rightwardly free of the stud 6 at its left end, but such movement is restricted by the abutment of a collar 17 on the shaft with the left side of the standard 5.

50 When the end gate 12 is in its supporting position the mandrel 9 is rotatably supported in an operative position in which it is in true parallel relation with respect to the guide rail 15. Supported by the left and right standards 2 and 3 is a longitudinal rod 18 which is also in true parallel relation to the guide rail 15 and on which there is slidably and tiltably mounted a carriage 19 having a sleeve bearing 20 embracing the rod 18. This carriage is also provided with an approximately semi-circular and forwardly extending arm portion 19' having a downwardly extending shoe portion 21 disposed directly above, and adapted to be slidably supported by, the guide rail 15. At the upper forward end of the carriage arm 19' there is provided a weight or hand-piece integrally formed with the arm and disposed substantially above the guide rail 15.

70 On the right side of the carriage 19 there is a boss 22 which substantially overlies the longitudinal rod 18. A resurfacing tool 23 is slidably mounted on the boss 22 for movement into and out of operative position with respect to the record 10. When the resurfacing tool is in an operative position it is adapted to cut away a surface layer of the record material as the record

is rotated and the carriage 19 is steadily moved across the record, the base plate 1 being provided with an opening 24 through which the cut-away surface layer, or record shavings, may pass as into a suitable container not shown. In order that the carriage 19 may be moved across the record coincidentally with the rotation of the mandrel 9, there is secured on the sleeve bearing 20 a collar 25 carrying a rearwardly extending and resilient arm 26 bearing a feed nut 27 at its 10 rearward end. When the carriage arm 19' is in its normal lowered or operative position, the shoe 21 being supported by the guide rail 15, the feed nut 27 engages the underside of a feed screw 28 15 rotatably supported by the standards 2 and 4 and having a shaft 28' at its left end carrying a pulley 29. The pulley 29 may be coupled, as by a suitable belt, to a pulley 30 located on the shaft 1 alongside of the pulley 29. A rotation of the mandrel 9 will then provide rotational movement 20 of the feed screw 28 to effect a longitudinal movement (in a left hand direction) of the carriage 19 with respect to the mandrel. It is thus apparent that with this arrangement an upward tilting movement of the carriage arm 19' will 25 cause the resurfacing tool 23 to be moved away from the record 10, and the feed nut 27 to be moved downwardly out of engagement with the feed screw 28, thereby permitting the carriage to be manually moved along the record 10. Such 30 upward tilting movement of the carriage arm 19' is however limited by the abutment of a rearwardly and downwardly extending arm 31 provided on the carriage with a stop 32 suitably comprising a reenforcing rib extending along the 35 rear edge of the opening 24.

For effecting rotational movement of the mandrel 9 there may be employed a suitable electrical motor M, shown diagrammatically in Fig. 2, which may be aptly located on the underside of the base plate 1 and coupled, as by a belt, to a pulley 33 secured on the shaft 7, the base plate 1 being provided with an opening 34 through which the motor drive belt may pass. The motor M is serially connected with a single-pole one-way toggle switch 74 in a power circuit 75 which is adapted to make connection with a suitable source of power as by way of a plug 76, the motor M being thus controlled by the switch 74. This switch is adapted to be automatically operated to "off" and "on" positions by the respective forward and return movements of the carriage 19. For this reason the switch 74 is preferably located on the top side of the base plate 1 in its left rearward portion as shown in Figs. 1 and 2. Extending forwardly of the switch 74 is an actuating arm 77 suitably biased so as to snap into its respective "off" and "on" positions, indicated by the respective left and right positions shown in Fig. 1, by reason of the toggle 50 nature of the switch.

The switch 76 is preferably turned slightly in a counter-clockwise direction so that the actuating arm 77 will project further forwardly when it is in its leftward or "off" position than it will 65 when it is in its rightward or "on" position. On the carriage there are provided left and right brackets 78 and 79 which are arranged to contact the switch arm 77 for operating the switch 74 by the movement of the carriage. The bracket 70 78, which is secured to the collar 25 of the carriage sleeve 20, is arranged to slightly clear the switch arm 77 when the arm is in its "on" position; however the bracket 79, which is secured to the carriage arm 31 by the screws 80, is U- 75

shaped and suitably extended rearwardly to encounter the switch arm 77 when the arm is in its "on" position. By such encountering the switch arm 77 is moved leftwardly to "off" position as the carriage 19 is moved forwardly in a leftward direction into its terminal position. The terminal movement of the carriage will thus stop the machine. As the carriage 19 is returned to initial position the bracket 78 will encounter the switch arm 77 when the carriage reaches an intermediate position in its return travel and thereby move the switch arm rightwardly from "off" position to "on" position so as to restart the machine.

15 The resurfacing tool 23 comprises a knife bar 35 carrying a knife blade 36 at its inner or lower end. The knife bar 35 is slidably mounted in an opening 35' provided in the boss 22 for movement towards and away from the record 10 so as to move the resurfacing tool, or the knife blade 36 which forms a part thereof, into and out of operative position with respect to the record. The upper end portion of the knife bar 35, which projects above the boss 22, is reduced in diameter and is extended loosely through the top wall of a hollow cap 37 which fits slidably over the boss 22. On the upper extremity of the knife bar 35 there is provided a head 38 for limiting the upward movement of the cap 37 with respect to the knife bar. The cap 37 is normally urged against the head 38 by means of a resilient coupling between the knife bar 35 and the cap 37, which coupling is adapted to yieldingly move the knife bar 35 downwardly so as to bring the knife blade 36 into proper engagement with the record 10 as the cap 37 is moved downwardly. Such resilient coupling may comprise a suitable compression spring 39 (see Fig. 7) coiled about the reduced diameter portion of the knife bar 35 between the top of the cap 37 and an adjustable collar 40 provided on the knife bar.

Movement of the cap 37 is guided by means of a guide rod 41 secured to the cap 37 by a headed screw 42 and slidably mounted in an opening 45 which extends through the boss 22 in parallel relation to the opening 35' through which passes the knife bar 35. In order that the resurfacing tool 23 may be normally maintained in an upward or inoperative position, the cap 37 is biased upwardly by means of a compression spring 43 coiled about the guide rod 41 between the boss 22 and the top wall of the cap 37. Such upward or inoperative position of the resurfacing tool 23 is determined by the abutment of a collar 44, secured to the lower end portion of the knife bar 35 by a set screw 45, with the underside of the boss 22.

For moving the resurfacing tool 23 into operative position, there is provided an actuating lever 46 which is pivotally supported by a post 47 secured by a press fit, as shown in Fig. 9, to the boss 22 and extended rightwardly thereof. A downward movement of the lever 46 into a position such as is shown in Fig. 2, yieldingly moves the resurfacing tool 23 into operative engagement with respect to the record 10 by means of a suitable coupling between the lever 46 and the cap 37 comprising a link member 48. The lower end of the link member 48 is pivotally connected to a short arm 49 of the lever 46 by a pivot screw 50 and the upper end is provided with a longitudinal slot 51 through which passes a shoulder screw 51 threading into the right wall of the cap 37. The lower portion of the link member 48 is in the form of a gooseneck so that it will

remain clear of the hub of the lever 46 as the lever is swung downwardly in the setting of the resurfacing tool; the gooseneck portion is adapted, however, to engage the hub of the lever 46 to limit the downward movement of the lever to a position in which the axis of the pivot screw 50 is slightly past dead center with respect to the pivot axes of the lever 46 and of the shoulder screw 52. It will therefore be apparent that the lever 46 is releasably locked whenever it is in its operative or downmost position by reason of the upward biasing force exerted on the cap 37 by the spring 43. It is further apparent that a slight upward or "tripping" movement imparted to the lever 46 to return the pivot screw 50 across the dead center line aforementioned will effect the release of the resurfacing tool from set position.

With the above form of setting mechanism for the resurfacing tool there may be very desirably provided suitable clamping means, which are operated by the movement of the lever 46 through the end portion of its downward travel, for fixedly holding the resurfacing tool 23 in its operative position. These clamping means may comprise a pin 53 slidably mounted in the boss 22 for transverse movement with respect to the movement of the knife bar 35. The inner end of the pin 53 abuts against the knife bar 35, whereas the outer end has a rounded portion projecting slightly beyond the side wall of the boss 22, as shown in Figs. 9 and 10. On the post 47 there is pivotally mounted a cam member 54 suitably comprising a sleeve 55 embracing the post 47 and an integral disc 56 having an open sector of substantially 90°, the disc being mounted adjacent to the side wall of the boss 22. The inner wall of the disc 56, along the lower radial line 57 shown in Fig. 7, is suitably beveled to form a cam face 58 which is adapted to slidably contact the outer end of the pin 53 to press the pin tightly against the knife bar 35. The actuating lever 46 is preferably pivotally mounted on the sleeve 55 of the cam member 54, the lever 46 and the cam member 54 being retained on the post 47 by a headed screw 59 threaded into the end of the post. On the hub of the lever 46 there is a lateral pin 60, shown in Fig. 2, which extends within the open sector of the disc 56. The angular travel of the lever 46 is somewhat greater than the angle of the open sector of the disc 56 so that, in setting the resurfacing tool into operative position, the pin 60 will first traverse the open sector of the disc 56 and then encounter the upper wall of the open sector to turn the cam member 54 through a small angular displacement in a counterclockwise direction. Such movement of the cam member 54 will cause the pin 53 to be pressed, as by the cam face 58, against the knife bar 35 so as to clamp the bar in its set position. In the release of the resurfacing tool 23 from set position, the pin 60 will first traverse the open sector of the disc 56 and then the pin 60 will encounter the lower wall of the open sector of the disc 56, as along the radial line 57, and turn the cam member sufficiently in a clockwise direction to free the cam face 58 from the pin 53, thereby unclamping the knife bar 35.

The mandrel 9 is slightly tapered so that a record may closely fit the mandrel and be yieldably held thereon by the friction between the record 70 and the mandrel. Usually considerable force is required to remove a record from the mandrel after it has been suitably mounted thereon. For facilitating the removal of a record there is commonly provided a record ejecting means which 75

may comprise a record ejecting member 61 having a hub 62 (see Figs. 1 and 6) pivotally mounted on a short rod 62' supported at one end by the guide rail 15 and at the other by the intermediate standard 5. Pivotally connected to the upper right end portion of the member 61 is a suitable record engaging shoe 63 (see Fig. 5) which is positioned slightly to the left of the adjacent end of the record 10 mounted on the mandrel 9. Along the left side of the member 61 there is secured a suitable handpiece 64, as by the screws 65, for facilitating the manual operation of the record ejecting means. The member 61 is also provided with a downwardly extending arm 66 which passes through an opening 67 in the base plate 1 and normally abuts against the rightward side of the opening, as by the weight of the member 61 and handpiece 64, to define the unoperated position of the record ejecting means. In operating the record ejector the handpiece 64 is swung upwardly about the rod 62' so as to bring the record engaging shoe 63 into engagement with the record to push the record off the mandrel, the operated position of the record ejector being defined by the impingement of a short V-shaped arm 68 on the member 61 with the upper surface of the base plate 1.

In phonograph record shaving machines there is also commonly provided a mandrel brake which is operated as an incident of operating the record ejecting means. The mandrel brake may comprise a vertically disposed arm 69 pivotally mounted on the rearward end portion of the rod 62' and carrying at its upper end a shoe 70, commonly made of felt, which is adapted to engage the adjacent end of the mandrel 9 for retarding, by friction, the rotation of the mandrel. The brake arm 69 is provided with a forwardly extending pin 71 which is resiliently connected to a rearwardly extending pin 72 provided on the record ejecting member 61 and extending along the right side of the pin 71, as shown in Figs. 1 and 6, the resilient connection being effected by a torsional spring 73 which is coiled about the hub 62 of the member 61 and hooked at its ends about the respective pins 71 and 72. By these means the brake arm 69 is adapted to be yieldingly moved in a clockwise direction, so as to urge the brake shoe 70 against the left end of the mandrel, as the record ejecting means are operated to remove a record from the machine.

The above described structure and mechanism are common to record shaving machines heretofore manufactured and used, and form a part of the present invention only in so far as they are related to or combined with other mechanism hereinafter described.

In my invention I provide means for improving, facilitating and safeguarding the operation of the machine. These means comprise interlocking means which prevent the operator from removing a record from the machine while the resurfacing tool is in an operative position. When it is desired to remove a record from the machine, as for example at the end of a resurfacing operation, the operator will first release the resurfacing tool. Such release permits the end gate to be opened and renders the record ejecting means operable. In order to render the resetting of the resurfacing tool more convenient, the operation of the record ejecting means is arranged to automatically return the carriage to a position wherein the resurfacing tool will overlie a properly mounted record. The resurfacing tool may then be immediately set into operative position after a subse-

quent record is mounted on the machine. In order to render this setting of the resurfacing tool more accurate, I provide improvements in the setting mechanism for the resurfacing tool which are unusually well adapted to enable the resurfacing tool to be consistently set at substantially even depths of cut. After the resurfacing tool is properly set, the next operation in the resurfacing of a record is to return the carriage to its initial position. Before a return movement can be imparted to the carriage, the carriage arm must be lifted upwardly to disengage the feed nut from the feed screw. It is therefore possible for the operator to inadvertently scrape the feed nut along the feed screw during such return of the carriage; in order that this may not occur, however, I provide means adapted to prevent any possible damage to the feed nut and the feed screw, as by a scraping of one or the other, during such return of the carriage. These means comprising my invention will now be described in detail.

It is important that the resurfacing tool be released from operative position before a record can be removed from the machine; otherwise the removal of a record while the carriage is in a position wherein the resurfacing tool overlies the record may cause the record surface to be marred and the blade of the resurfacing tool to be broken. The means for preventing the removal of a record from the machine while the resurfacing tool is in operative position may comprise a locking member 81, disposed along the right side of the base plate 1 as shown in Figs. 1 and 7, for releasably locking the end gate 12 in its closed or supporting position. Reference being had particularly to Fig. 7, there will be seen a downwardly extending arm 82 on the front portion of the end gate 12 which, in the opening movement of the end gate is adapted to encounter a turned up lug 83 at the forward end 40 of the locking member 81. The member 81 is provided with the front and back longitudinal slots 84 and 85 (shown in Fig. 1) through which pass the respective shoulder screws 86 and 87, each threading into the base plate 1. The locking member 81 is thus slidably mounted for rearward movement so that the lug 83 may be moved out of the path of the arm 82 on the end gate, and thereby render the end gate free for opening movement. The member 81 is urged forwardly 45 into its locking position by a tension spring 88 connected between the rearward end portion of the member 81 and a pin 89 on the base plate 1; rearward movement of the member 81 is effected by the release of the resurfacing tool from operative position as is now described.

The rearward end portion of the member 81 is bent leftwardly and then turned up to form an ear 90 having an open slot 91 through which slidably passes a lateral pin 92 carried by a cross bar 93 located slightly above the base plate 1 and extending throughout the length of travel of the carriage 13, as shown in Figs. 1 and 7. The bar 93 has left and right turned over end portions which extend upwardly to form its respective left and right supporting arms 94 and 95. The lower end of the rightward arm 95 carries the lateral pin 92; whereas the upper end of this arm is pivotally connected by a shoulder screw 96 to a rearwardly extending arm 97 secured to the standard 3 by the screws 98. The leftward arm 94 of the bar 93 is pivotally supported, at its upper end, by a bracket 99 which is secured to the base plate 1 by the screws 100. Thus the bar 93 is mounted for swinging move- 75

ment, and is adapted, as it is swung rearwardly, to cause the locking member 81 to be moved out of locking position by the coaction between the pin 92 and slot 91.

5 In order that the bar 93 may be moved rearwardly by the release of the resurfacing tool 23 from operative position there is pivotally mounted on the right side of the carriage a U-shaped member 101 having its left and right legs respectively pivoted on the inner and outer ends of a long shoulder screw 102 threaded into the boss 22 as shown in Figs. 1 and 7. The left leg of the member 101 is provided with an arm 103 which extends downwardly in front of the cross bar 93; whereas the right leg of the member 101 is provided with a forwardly extending arm 104 which is turned slightly upwardly so as to contact a cam 105 on the hub of the lever 46 when the lever 46 is in its rearward or inoperative position. As the arm 104 is brought into contact with the cam 105 the member 101 is turned in a counterclockwise direction so as to cause the cross bar 93 to be moved rearwardly, as by the arm 103, such rearward movement of the bar 93 causing the locking member 81 to be moved into an inoperative position. However upon setting the resurfacing tool into operative position, the member 81 will again return to its locking position as by the spring 88.

- the screw 102, a bail portion 149 straddled by the member 181, and a forwardly extending arm 141 bent at right angles to the bail portion and pivoted on the outer end of the shoulder screw 102.
- 5 The arm 141 contacts the underside of the short arm 49 of the lever 46 when the lever is in its downmost or operated position. A clockwise movement of the member 137, such as may be imparted thereto by pushing the button 117 downwardly to effect a forward movement of the bar 130 will thus cause a clockwise or upward "tripping" movement of the lever 46 to effect the release of the resurfacing tool 23 from operative position.
- 10 15 The means for partially returning the carriage 19 to its initial position as an incident of operating the record ejecting means are shown in Figs. 1, 5 and 8. These means comprise a bar 142 pivotally supported at its rightward end by a shoulder screw 143 threading into a boss 144 on the inner side of the guide rail 15, and extending leftwardly therefrom along the inner wall of the guide rail. When the bar 142 is in its unoperated position, as shown in Figs. 5 and 8, the upper edge 20 25 of its left end portion extends along, at a distance slightly below, the upper edge of the guide rail 15, whereas the upper edge of the remaining portion of the bar 142 is suitably considerably below the guide rail. The left end portion of the bar 142 is adapted to be swung upwardly so as to raise the carriage arm 19' and to disengage the feed nut 27 from the feed screw 28. For this reason the left end portion of the bar 142 is supported by a lever 145 having its leftward end pivotally connected to a boss 146 on the inner leftward end of the guide rail, as by a shoulder screw 147, the lever extending rightwardly therefrom through substantially half the length of the guide rail. The right end of the lever 145 is coupled to 30 35 the bar 142 and for this purpose it is provided with a longitudinal slot 148 through which slidably passes a lateral pin 149 carried by the bar 142 at a position substantially midway of the length thereof. The lever 145 is supported intermittently thereof by the engagement of its lower edge with the hub 62 of the record ejecting member 61, the hub 62 having a cut-away segment 150 through which the lower portion of the lever 145 passes. As the record ejecting member 61 is 40 45 turned in a clockwise direction to eject a record, the right end of the lever 145 is tilted upwardly about the shoulder screw 147 by the coaction between the hub 62 and the lever 145. The left end of the bar 142 is thereby tilted upwardly about 50 55 the shoulder screw 143 into a position substantially indicated by the dash-dot lines 151' shown in Fig. 8.
- When the carriage 19 is in the end portion of its forward travel (its terminal position being indicated in dash dot lines in Fig. 5) the upward tilting movement of the bar 142, as caused by the movement of the record ejecting member 61 through the initial portion of its travel, will cause the carriage arm 19' to be raised, and will thereby 60 65 cause the feed nut to be disengaged from the feed screw. As the member 61 is moved further in the ejection of a record from the machine, the carriage 19 is adapted to be slidably moved rightwardly through a portion of its return travel by 70 75 the impingement of an upwardly extending arm 151 provided on the member 61 with the left side of the shoe 21 on the carriage, the arm 151 being offset forwardly as shown in Fig. 2 in order that it may suitably contact the shoe 21. Such return movement of the carriage is insufficient, however,

to cause the switch 74 to be operated to "on" position, so that the machine will not be thereby restarted. When the record ejecting member 61 is returned to unoperated position, the bar 142 will be lowered so that the carriage shoe 21 will again rest on the guide rail 15, the feed nut 27 then again being engaged with the feed screw 28. Since the resurfacing tool 23 had to be released from operative position before the record ejector could be operated, and since the carriage 19 is 10 partially returned to move the resurfacing tool to a position overlying the record as an incident of operating the record ejector, the machine will be in condition so that the resurfacing tool may be immediately reset into operative position after a 15 subsequent record is mounted on the machine.

In order that the resurfacing tool 23 may be consistently set at a substantially even depth of cut, it is important that the knife bar 35 be freely slidably movable within the opening 35' through 20 which the knife bar passes, particularly since the knife bar is spring-pressed into engagement with the record. It has therefore been important to have the bar 35 fit somewhat loosely in the opening 35', and to provide a suitable lubricating oil 25 to facilitate such free sliding movement. However the pressing of the knife bar 35 against one side of the opening, as in the clamping of the bar for fixedly holding the resurfacing tool in operative position, has tended to squeeze out the lubricating oil and to cause considerable transverse movement of the knife bar. As a result of the extraneous movement of the bar and of the tendency for considerable friction to develop by reason of such squeezing out of the lubricating oil, which 30 friction restricts the free movement of the bar, the blade 36 may tend not to be consistently pressed into the record surface at the same depth for repeated settings of the knife.

In my invention I provide means for avoiding 40 the above difficulties, which means comprise two flat faces 152 respectively milled along a portion of the knife bar on opposite sides thereof. Within the lower and upper portions of the boss 22 there are provided the respective hardened rollers 153 and 154 which may be mounted therein by way of suitable openings provided in the underside of the boss 22, and which may be suitably held therein by screw plugs, such as the plug 155 for the roller 154 shown in Fig. 9. The rollers 153 and 154 are mounted transversely of the knife bar 35 and are extended longitudinally thereof slightly within the opening 35' so as to slidably contact one of the flat faces 152 of the knife bar. The other of the flat faces 152 slidably contacts the inner end of the clamping pin 53 and also the lower and upper pins 156 and 157 which are disposed in suitable openings in the right side of the boss 22. These pins are biased against the knife bar 35 by the compression 60 springs 158 and 159, which are disposed between the respective pins and the respective screw plugs 158' and 159'. By these means the knife bar 35 is urged against the rollers 153 and 154 by the force of the compression springs 158 and 159, this force, however, being insufficient to retard the free sliding movement of the bar. When the bar 35 is clamped, as by the clamping pin 53, it is urged against the roller 153 and 154 in the same direction as it is urged by the biasing springs 158 65 and 159. Therefore, as the knife bar 35 is clamped, substantially no transverse movement thereof takes place, with the result that the lubricating oil is not squeezed out between the knife bar 35 and the opening 35'. Consequently the 70 75 80 85 90 95 98 99

knife bar remains freely slideable within the opening 35' so that the resurfacing tool may be consistently set at a substantially even depth of cut.

In operating the machine, as after the setting 5 of the resurfacing tool 23 into operative position with respect to a newly mounted record, the carriage 19 will be returned to initial position, such further return of the carriage being adapted to operate the switch 74 into "on" position so as to 10 restart the machine. In the manual return of the carriage 19 it is important that the operator maintain the carriage arm 19' in such upward tilted position as will avoid a scraping of the feed nut 27 on the feed screw 28. In my invention I 15 provide means for preventing such possible scraping by maintaining the carriage wholly released from the carriage feeding means as the carriage is manually returned to initial position. These means may suitably comprise a parallel bar 160 20 mounted on the inner side of the guide rail 15 by means of the left and right parallel motion supporting links 161 and 162 pivotally connected to the respective ears 161' and 162' of the bar 160, the links 161 and 162 being also pivotally 25 connected to the respective inwardly extending bosses 163 and 164 on the guide rail 15 by means of the respective shoulder screws 163' and 164'. The bar 160 is urged rightwardly against a pin 165 on the guide rail 15 by means of a tension spring 30 166 connected between an ear 167 on the link 161 and a pin 168 secured on the base plate 1. In such rightward position of the bar 160 the links 161 and 162 are slightly inclined to the right and the bar 160 is caused to project above and parallel 35 to the guide rail 15.

The left end of the bar preferably projects a small distance above the left end portion of the bar 142 when the bar 142 is in its most upward or operated position. In the partial return of the 40 carriage, as by the operation of the record ejecting means, the left end of the bar 160 will then act as a suitable stop for limiting the return movement of the carriage. When the carriage arm 19' is raised above the bar 160 the carriage may be 45 returned to its initial position. After the carriage arm 19' is moved to a position overlying the bar 160, the bar will suitably maintain the carriage arm 19' in its upward tilted position throughout the return movement of the carriage, thereby 50 maintaining the feed nut free of the feed screw. The length of the bar 160 is however limited to permit the carriage to move into a normal operating position, wherein the carriage arm 19' is supported by the guide rail 15, when the carriage 55 reaches its initial position.

As the carriage is then fed forwardly the left end of the shoe 21 will encounter the right end of the bar 160 and move the bar leftwardly and downwardly to a position wherein the upper edge 60 of the bar 160 will be level with the upper edge of the guide rail 15, the upper corner of the right end of the bar 160 being suitably rounded to permit the shoe 21 to slide above the bar and the weight of the carriage arm 19' being sufficient to 65 maintain the bar 160 in its downward position against the force of the spring 166. As the carriage shoe 21 rides off of the bar 160, the bar will spring upwardly to its normal position shown in Fig. 8. In this position the bar will be again effective for limiting the partial return of the carriage 70 as the carriage is moved by the record ejecting means and for preventing possible scraping of the feed nut against the feed screw as the carriage is manually returned to initial position.

75 I have herein shown automatic means for par-

tially returning the carriage to initial position, and means for maintaining the carriage released from the carriage feeding means as the carriage is then manually returned through the remaining portion of its travel; it will be understood, however, that although I secure special advantages, mentioned hereinbefore by employing both these means together, I may employ either one of these means without the other. It will be further understood that I intend no limitation as to 10 the length of the bar 160; for example, if the automatic carriage returning means be omitted, I may extend the bar 160 through the terminal position of the carriage. It will be seen, as for example by reference to Fig. 5, that if the carriage is advanced or fed through a portion of its travel to an intermediate position overlying the bar 160 and then stopped and returned to initial position, the upward tilting of the carriage, to release the carriage from the carriage feeding means, will permit the bar 160 to move upwardly into operative position, as by reason of the spring 166, to maintain the carriage released from the carriage feeding means. This same action would 15 of course occur as the carriage is returned from its terminal position, if the bar 160 were extended through the terminal position of the carriage.

Although I have described a preferred embodiment of my invention, it is to be understood that the same is subject to many changes and modifications without departure from the scope thereof, which I now undertake to express according to the following claims.

I claim:

1. In a phonograph record shaving machine 35 having a support on and from which a record is mounted and removed; the combination of a tool-carriage capable of forward and return movements across said support; a member moved incidental to the removal of a record from the machine; and means operatively connected with said member for causing a partial return of said tool-carriage as an incident to a record removal.

2. In a phonograph record shaving machine 40 having means for supporting a record; in combination, a carriage movable across the record; means for ejecting a record from said supporting means; and means, operatively connecting said record ejecting means with said carriage, for moving said carriage as an incident of operating 45 said record ejecting means.

3. In a phonograph record shaving machine 50 having means for supporting a record; in combination, a carriage capable of forward and return movements across the record; a record ejecting means; and means, operated by said record ejecting means, for imparting return movement to said carriage.

4. In a phonograph record shaving machine 55 having means for supporting a record; in combination, a carriage capable of being advanced and returned across the record, movable means for ejecting a record from said supporting means, means operated incidental to the movement of said record ejecting means for imparting return 60 movement to said carriage, and a stop for restricting said return movement of said carriage.

5. In a phonograph record shaving machine 65 having means for supporting a record; in combination, a carriage movable across the record; carriage advancing means releasably connected with said carriage; movable means for ejecting a record from said supporting means; and means, operated incidental to the movement of said record ejecting means, for releasing said carriage 70

from said carriage advancing means and imparting return movement to said carriage.

6. In a phonograph record shaving machine having means for supporting a record: in combination, a carriage movable across the record; carriage advancing means releasably connected with said carriage; record ejecting means movable between unoperated and operated positions; and means, operated incidental to the act of moving said record ejecting means from unoperated to operated positions, for releasing said carriage from said carriage advancing means and imparting return movement to said carriage, said last named means being arranged to reconnect said carriage with said carriage advancing means as said record ejecting means is moved from operated to unoperated positions.

7. In a phonograph record shaving machine having a mandrel for supporting a record to be resurfaced: the combination of a record ejector; a tool-carriage; driving means; means for coupling said tool-carriage with said driving means; and means, operatively connecting said coupling means with said ejector, for rendering said coupling means inoperative as an incident of operating said ejector.

8. In a phonograph record shaving machine having a support for a record to be resurfaced: the combination of a record ejector; a tool-carriage movable relative to said support; means for moving said tool-carriage comprising a rotatable feed screw and a feed nut mounted on said tool-carriage and normally engaging said feed screw; and means, controlled by said record ejector, for moving said feed nut out of engagement with said feed screw when said ejector is operated.

9. In a phonograph record shaving machine having a mandrel for supporting a record to be resurfaced: the combination of a record ejector; a tool-carriage capable of forward and return movements across a supported record, and tiltable away therefrom; and means, operated by said ejector, for first tilting said tool-carriage and then imparting a return movement to the same.

10. In a phonograph record shaving machine having a mandrel for supporting a record to be resurfaced: the combination of a record ejector; a tool-carriage movable across a supported record and tiltable away therefrom; and means, operatively connecting said record ejector with the carriage, for tilting the latter as an incident of removing a record from the machine.

11. In a phonograph record shaving machine having means for supporting a record: in combination, a carriage; a resurfacing tool on said carriage movable into operative position relative to the record; and means, controlled by said resurfacing tool, for preventing the removal of a record from the machine.

12. In a phonograph record shaving machine having means for supporting a record; in combination, a carriage movable across the record; a resurfacing tool on said carriage movable into an operative position relative to the record; record ejecting means; and means, operatively connecting said resurfacing tool with said record ejecting means, for obstructing the operation of said record ejecting means while said resurfacing tool is in operative position.

13. In a phonograph record shaving machine having means for supporting a record: in combination, a carriage movable across the record; a resurfacing tool on said carriage movable into

an operative position relative to the record; record ejecting means; means for locking said record ejecting means against operation; and means, operated by said resurfacing tool as an incident to the movement of the tool from operative position, for rendering said locking means inoperative. 5

14. In a phonograph record shaving machine having a mandrel for supporting a record: the combination of an end-gate for said mandrel having a latched position; a carriage; a resurfacing tool on said carriage; means for setting said tool into operative position relative to the record; and means, controlled by said tool-setting means, for locking said end-gate in said latched position. 10

15. In a phonograph record shaving machine having a mandrel for supporting a record: in combination, an end gate for said mandrel movable into supporting and non-supporting position, a carriage, a resurfacing tool and said carriage movable into operative position relative to the record, means for locking said end gate in supporting position, and means operated incidental to the movement of said resurfacing tool 25 out of operative position for rendering said locking means inoperative.

16. In a phonograph record shaving machine having means for supporting a record: in combination, a carriage capable of being advanced 30 and returned across the record; a resurfacing tool on said carriage movable into operative position relative to the record; means for imparting return movement to said carriage; and means, operatively connecting said resurfacing 35 tool with said carriage returning means, for rendering said returning means inoperative while said resurfacing tool is in operative position.

17. In a phonograph record shaving machine having means for supporting a record: in combination, a carriage capable of being advanced 40 and returned across the record; a resurfacing tool on said carriage movable into operative position relative to the record; record ejecting means; means for imparting return movement 45 to said carriage as said record ejecting means is operated; and means, operatively connecting said resurfacing tool with said record ejecting means and carriage returning means, for rendering said record ejecting means and carriage returning 50 means inoperative while said resurfacing tool is in operative position.

18. In a phonograph record shaving machine having means for supporting a record: in combination, a carriage capable of being advanced 55 and returned across the record; a resurfacing tool on said carriage movable into operative position relative to the record; record ejecting means; means for imparting return movement to said carriage as said record ejecting means is 60 operated; and means, connecting said resurfacing tool with said carriage returning means, for locking said carriage returning means against operation while said resurfacing tool is in operative position.

19. In a phonograph record shaving machine having means for supporting a record: in combination, a carriage capable of being advanced 70 and returned across the record; a resurfacing tool on said carriage movable into operative position relative to the record; record ejecting means; means for effecting return movement of said carriage as an incident of operating said record ejecting means; and means, connecting said resurfacing tool with said record ejecting 75

- means, for rendering said ejecting means inoperative while said resurfacing tool is in operative position.
20. In a phonograph record shaving machine having a mandrel for supporting a record to be resurfaced: the combination of a tool-carriage movable across a supported record and tiltable upwardly therefrom; and means operated as an incident of tilting said tool-carriage for maintaining the same in a tilted position.
21. In a phonograph record shaving machine having means for supporting a record: in combination, a carriage capable of being advanced and returned across the record; carriage advancing means; coupling means biased to normally connect said carriage with said carriage-advancing means and releasable to disconnect the same; and means, rendered operative incidental to the release of said coupling means, for maintaining said carriage disconnected from said advancing means.
22. In a phonograph record shaving machine having means for supporting a record: in combination, a carriage capable of being advanced and returned across the record; carriage advancing means; coupling means normally connecting said carriage with said carriage-advancing means and releasable to disconnect the same; and means, operative throughout at least a substantial portion of the return movement of said carriage, for maintaining said coupling means released.
23. In a phonograph record shaving machine having means for supporting a record: in combination, a pivotally and slidably mounted carriage capable of being slidably fed from an initial position to other positions along the record; carriage feeding means; means for coupling said carriage with said carriage feeding means, and means being rendered inoperative while said carriage is in a pivotally moved position; and means for maintaining said carriage in said pivotally moved position as said carriage is returned to said initial position.
24. In a phonograph record shaving machine having means for supporting a record: in combination, a pivotally and slidably mounted carriage capable of being slidably fed across the record; carriage feeding means rendered inoperative while the carriage is in a pivotally moved position; record ejecting means; means for partially returning said carriage as an incident of operating said record ejecting means; and means for slidably supporting said carriage in said pivotally moved position to maintain said carriage feeding means inoperative throughout the further return of said carriage.
25. In a phonograph record shaving machine having means for supporting a record: in combination, a pivotally and slidably mounted carriage capable of being slidably fed across the record; carriage feeding means rendered inoperative while the carriage is in a pivotally moved position; means for slidably supporting said carriage in said pivotally moved position throughout the carriage travel, said means being moved into an inoperative position as said carriage is fed through said predetermined portion; and means for moving said carriage supporting means into an operable position when said carriage is fed at least beyond said predetermined portion.
26. In a phonograph record shaving machine having a mandrel for supporting a record to be resurfaced: the combination of a frame; an end gate for said mandrel movable into supporting and non-supporting positions; means for locking said end gate in supporting position; a tool-carriage mounted on said frame and movable with relation to the mandrel; means on said carriage for moving the tool into record-engaging position; and means on said frame for moving said tool from record-engaging position and coordinately rendering said locking means inoperative.
27. In a phonograph record shaving machine having a record supporting mandrel: the combination of an end-gate for said mandrel movable between supporting and non-supporting positions; a releasable latch for holding said end-gate in supporting position; separately operable end-gate locking means; a carriage movable with relation to the mandrel; a resurfacing tool on said carriage; means on said carriage for moving said tool into record-engaging position; and manipulative means, disposed in the vicinity of said latch so that it is adapted for operation concurrently with the release of the latter and by a single manipulation of the hand, for rendering said locking means inoperative and causing said tool to be moved out of record-engaging position.
28. In a phonograph record shaving machine having means for supporting a record: in combination, a carriage movable across the record, a resurfacing tool comprising a knife bar slidably mounted on said carriage, means for biasing said knife bar transversely of the direction of its sliding movement, and clamping means for said knife bar operable so as to force the bar in the same direction as said biasing means.
29. In a phonograph record shaving machine having means for supporting a record: in combination, a carriage movable across the record; a knife bar slidably mounted on said carriage, having two flat surface portions disposed substantially directly opposite of each other partially along the length thereof; a plurality of roller members slidably contacting one of said flat surface portions; means, contacting the other of said flat surface portions, for biasingly maintaining said bar in slidable engagement with said roller members; and clamping means contacting said other flat surface portion, operable to force said bar against said roller members for locking the bar against sliding movement.

RICHARD M. SOMERS.

CERTIFICATE OF CORRECTION.

Patent No. 2,184,365.

December 26, 1939.

RICHARD M. SOMERS.

It is hereby certified that error appears in the printed specification of the above numbered patent requiring correction as follows: Page 8, first column, line 15, claim 6, for "cariage" read carriage; line 63, claim 12, after the word "record" strike out the semicolon and insert instead a colon; and second column, line 21, claim 15, for "and" read on; page 9, first column, line 39, claim 23, for "and" read said; and that the said Letters Patent should be read with this correction therein that the same may conform to the record of the case in the Patent Office.

Signed and sealed this 12th day of March, A. D. 1940.
